UNITED STATES PATENT OFFICE.

WILLIAM T. JEFFERSON, OF CHICAGO, ILLINOIS.

EMBROIDERY-PATTERN.

1,067,923.

Specification of Letters Patent. Patented July 22, 1913.

Application filed September 11, 1911. Serial No. 648,769.

To all whom it may concern:

Be it known that I, WILLIAM T. JEFFERSON, a citizen of the United States, residing at Chicago, in the county of Cook and State 5 of Illinois, have invented certain new and useful Improvements in Embroidery-Patterns, of which the following is a specification.

The device of my invention is designed to 10 advertise and promote the sale of embroidering materials; and it consists, substantially, of a doll garment pattern of card-board or any like material suitable for such pattern, which pattern is perforated throughout the 15 portion or portions thereof designed to be embroidered, such perforations being adapted to receive the embroidering stitches and constituting a guide or chart for the application of the embroidery.

20 My invention is illustrated in the accompanying drawing, in which—

Figure 1 is a front elevation of a card-board doll garment pattern made in accordance with my invention and adapted to receive the embroidery on parts of the waist 25 and skirt portions thereof. Fig. 2 is a similar view of a card-board doll wearing an undergarment to the upper and lower portions of which the embroidery has been applied. Fig. 3 is a view of another dress pattern wherein the perforated parts have been embroidered. Fig. 4 is a back fragmentary view of a portion of the skirt pattern shown in Fig. 3, wherein a design to be embroidered 30 is printed on the pattern itself.

Referring to the drawing, 5 designates the 35 figure of a printed paper or card-board doll, and 6 designates as an entirety a doll garment pattern which may either be printed 40 on the figure 5 of the doll, as in Fig. 2, or may be made separate and adapted to be attached to the doll figure by the usual bent 45 clips 7. On the pattern 6 the plain or un-embroidered portions of the garment represented thereby may be indicated by printing, either plain or colored, such portions being indicated at 8; while portions to be embroidered are formed with closely set rows 50 or groups of perforations, as indicated by the parts marked 9 in Fig. 1, both to iden-

tify the parts to be embroidered and to facilitate the passage of the needle in embroidering the pattern. Individual groups of such perforations may be designated to receive different colors of embroidering silk 55 or other material by means of correspondingly colored portions of the pattern containing such groups of perforations, as indicated in Fig. 1. In Figs. 2 and 3 the embroidered parts of the garment patterns 60 therein shown are indicated at 10.

As a further aid to the child in working the embroidery, an embroidery pattern may be printed on either the back of the portion or portions of the pattern to be embroidered, 65 as indicated at 11 in Fig. 4. The printing of such pattern may, if desired, be in suitable colors to be followed in working the embroidery; and such pattern would preferably be printed on the back since that would 70 enable the child to either follow the printed pattern or disregard it and design an original pattern, whereas, where the pattern is printed on the front, the printed pattern 75 has to be followed to avoid an inartistic effect.

The device of my invention constitutes an interesting and instructive toy for children, who by the use of the device can readily 80 learn how to embroider simple patterns and to combine harmonious colors; the device being further well adapted to afford an attractive form of sample display of the embroidering materials which it serves to advertise.

85 I claim—

An embroidery pattern comprising a card-board doll having a printed face, arms and garment, said doll having perforations formed on the garment portion to receive 90 embroidery stitches and a detachable outer garment having a printed garment pattern, perforations for receiving embroidery stitches and a printed embroidery pattern 95 on the opposite side of said garment from said garment pattern.

W. T. JEFFERSON.
